UNITED STATES PATENT OFFICE.

JAMES E. WOOTAN, OF TACOMA, WASHINGTON.

MACHINE FOR MILLING BASE ORE.

1,320,302.

Specification of Letters Patent.

Patented Oct. 28, 1919.

Application filed April 8, 1919. Serial No. 288,454.

To all whom it may concern:

Be it known that I, JAMES E. WOOTAN, a citizen of the United States, residing at Tacoma, in the county of Pierce and State of Washington, have invented a new and useful Machine for Milling Base Ore, of which the following is a specification.

The object of my invention is to provide an improved machine for milling base ore of relatively simple construction and which will perform the work without the use of so much water as is used in machinery heretofore devised for work of this character. It is a particular object of my invention to provide a machine which can be manufactured at small cost and which will not readily get out of order. These and other objects of my invention I attain by the mechanism illustrated in the accompanying drawing, in which—

Figure 1 is a side elevation of the invention, with the troughs shown in section;

Fig. 2 is a top plan of my invention;

Fig. 3 is a vertical section on line 3—3 of Fig. 2;

Fig. 4 is a transverse section on line 4—4 of Fig. 1; and

Fig. 5 is a transverse section on line 5—5 of Fig. 2.

Like numerals designate like parts throughout the several views.

Referring to the accompanying drawings I provide a long trough 1 into which the ore to be separated is fed from chute 18, overflow being prevented by the cover plate 17. Trough 1 is supported from a series of uprights 2. Suitable arms 3 attached to the trough 1 are suspended adjustably by the screw eyes 4, which are adjustably supported from uprights 2 by suitable bolts 5. A vibratory motion is imparted to trough 1 by means of link 6 and cam 7. Cam 7 is mounted on shaft 8, which also carries a pulley 10. Pulley 10 is belted to pulley 11 on shaft 12. Shaft 8 is provided with a pulley 9, belted to a suitable source of power.

Mounted on the end of shaft 12 I provide a sprocket 13, connected by chain 14 to a suitable sprocket 15 attached to and driving the worm 16 which extends the length of the trough 1, approximately, as illustrated. I provide a short spout 19 at the upper end of trough 1 and opening into the short trough 20 to dispose of drippings at this end of the trough.

In the lower end of trough 1 I provide the series of spaced parallel plates 23 positioned close to the worm 16. The lower end of the trough is provided with a cut-out 60 washer 26 and a spout 21 through which the heavier material separated is discharged into trough 22. Positioned above and beyond spout 21 is a spout 24 over which the material passing over plate 23 is discharged into a second trough 25 positioned just beyond the trough 22. One plate 23 is used in operation of the machine if sand is going over with slimes. For this use put in the upper plate 23 and take the bottom 70 one out.

With the flotation system the pulp must be 15 to 25 per cent. solid to do good work. With my improved apparatus the pulp is put to the flotation as it comes from the 75 crusher. As the material is fed along the trough 1 by the flow of water the worm 16 discharges the heavy concentrates into trough 20. At the lower end of trough the spaced dividing plates separate the 80 slimes from the sand. The plates 23 are mounted in grooves in the sides of trough 1. The plates are spaced about $\frac{1}{8}$ inch apart which is sufficient to effect the desired division of the slimes from the sand. The 85 trough 1 is vertically adjustable by means of the screw eyes 4 and nuts 5. The cam 7 which has a link connection with the trough gives the latter a vibratory motion which causes the heavy sand to sink and 90 the slimes to float. The worm 16 is connected by sprocket chain 14 with the shaft 12 which in turn is operated with the connected shafts 8, and the latter is driven from any suitable source of power. 95

My apparatus classifies and separates the material into three grades.

What I claim is:

1. In a machine for milling base ore, the combination of a vertically adjustable 100 trough, a worm in the trough, spaced parallel plates positioned in the lower end of the trough in proximity to the worm, a spout through which material passing over the plates is conveyed, and a separate spout 105 opening out of the bottom of the trough through which the heavier material is discharged by the force of the flowing water and gravity.

2. In combination with the apparatus described in claim 1, means for giving the trough a vibratory motion. 110

3. In combination with the apparatus described in claim 1, means for giving the trough a vibratory motion, and means for the discharge and collection of heavy concentrates.
4. In a machine for classifying and separating ore into three grades, the combination of a main trough, means for adjusting the inclination of the trough, a worm extending approximately the length of the trough, means for discharging the material with water into the trough, spaced plates at
- 10

the lower end of the trough for separating the material into two grades, adjoining troughs into which said material is discharged from the main trough, a trough at the upper end of the main trough for the collection of heavy concentrates, means for rotating the worm to discharge heavy concentrates at the upper end of the main trough, and operatively connected means for agitating the main trough, substantially as and for the purposes described.

JAMES E. WOOTAN.
